UNITED STATES PATENT OFFICE

2,520,974

RUPTURED CARTRIDGE EXTRACTOR

Paul A. Spinnato, New Haven, Conn.

Application October 8, 1946, Serial No. 701,859

3 Claims. (Cl. 81—3.05)

(Granted under the act of March 3, 1883, as
amended April 30, 1928; 370 O. G. 757)

1

The invention described herein may be manufactured and used by or for the Government and for governmental purposes without the payment of any royalty thereon.

This invention relates to improvements in extracting devices and is directed more particularly to the provision of an improved device for extracting ruptured cartridge cases from the barrels of firearms.

The problem of removal of a ruptured cartridge case is difficult. A cartridge case which ruptures in a firearm at a crucial moment in combat requires speedy extraction thereof. While various devices have been conceived for the extraction of ruptured cases, such devices have been generally unsatisfactory.

Accordingly it is the principal object of this invention to provide a new and improved device whereby a ruptured cartridge case may be readily and speedily removed from the barrel of a firearm.

The specific nature of the invention as well as other objects and advantages thereof will clearly appear from a description of a preferred embodiment as shown in the accompanying drawings in which:

Fig. 1 is a fragmentary sectional view showing the device of the invention in extracting position in the firearm;

Fig. 2 is an enlarged top view of a portion of the device of the invention;

Fig. 3 is a perspective view of the rear end portion of the device of the invention;

Fig. 4 is an exploded view in perspective to show the forwardmost members of the device in disassembled relation; and

Fig. 5 is a sectional view on the line 5—5 of Fig. 2.

As will be described, the device of this invention is adapted to be introduced into the breech end of the barrel of a firearm and is so constructed as to be capable of extracting a seized, ruptured, headless shell upon which no positive hold can otherwise be obtained.

Frequently the rims or flanged heads of cartridge shells pull off during firing of the weapon so that the cases are left in the firearm. Obviously, such ruptured cases must be removed before the firearm can again be operated.

The device of this invention consists generally of a longitudinally-extending implement which is adapted to be inserted into both the barrel B and the ruptured cartridge C. The device is adapted to forcibly remove the case, both with speed and ease, from the barrel and without injury to the firearm.

It includes a tubular collet-like member 10 which has a more or less arrow-shaped head portion 12 having a flange-like rear surface 13 which is adapted to engage the forward edge of the

ruptured case. The member 10 is provided with one or more longitudinal slots 14 which extend rearwardly from the forward end thereof and terminate short of the rear end thereof in such a way as to render the tube 10 expansible and according to the preferred form of the invention as shown in the drawings there are four equally-spaced such slots 14.

There is also a spindle member 20 having an enlarged forward end portion 22 and a rear end portion which is exteriorly threaded as indicated at 24. Said member 20 extends rearwardly into the opening of member 10 and its head part 22 is formed to have a conical surface 23 on its rear side which is adapted to mate with the interior faces 25 of the slotted forward end portion 12 of the member 10. As will be explained, the arrangement is such that while the member 10 is more or less contractable so it may be readily inserted into the ruptured case C, it is, as previously stated, expansible so that after insertion to a sufficient extent the head 12 snaps over the end of the case so that its surface 13 engages the forward edge thereof.

A nut-like body or housing member 26 is provided which has a forward face 28 adapted to be in bearing engagement with the rear end face 30 of barrel B. This said member 26 has an interiorly threaded bore as indicated and into this bore is threaded an elongated sleeve member 32.

The forward end portion of the member 32 is provided with a T-slot indicated by 34 in Fig. 2, while its rear end portion 36 is formed to be of an irregular or polygonal shape in order that the same may be engaged by pliers, a ratchet wrench, or some other suitable tool or implement when the device is being used for extracting the ruptured cartridge cases in the manner later to be described. The said slot 34 has a reduced width at its forward end as shown in Fig. 5.

A joining or connecting member 40 has a forward portion 42 which threadedly engages the rear end portion of the spindle member 20 and a rear end portion 44 which is seated in the above-mentioned slot 34. The construction is such that an intermediate shank portion 45, which is of reduced diameter with respect to parts 42 and 44, may reside in the said reduced forward portion of the slot and the relative lengths of the wider portion of slot 34 of member 32 and part 44 of member 40 are such that the connector 40 may move longitudinally relative to the member 32.

A plunger member 50 is inserted into the member 32 and it is of such length and so arranged that its forward end portion threadedly engages the rear part 44 of the joining member 40 which is threaded interiorly. A coil-spring 52 of conventional construction surrounds the plunger 50. When the extracting device has been inserted

sufficiently into the cartridge so that the head 22 of the spindle member 20 and the head portion 12 of tubular member 10 is in advance of the forward marginal edge of the cartridge case C, the forward face 28 of the housing 26 will be in bearing engagement with the rear end face 30 of the barrel B.

For reasons of explanation of the invention it may be stated that a female type ratchet wrench has been found useful to position the extractor into the breech end of the barrel of a machine gun, regardless of whether the same is in gun position on the ground or in aircraft. Although when the device of the invention is used in connection with ball turrets, it is preferable to use a ratchet wrench which is flexible.

Thereupon, in order to operate the device and bring about extraction of the cartridge case, the member 32 will be moved outwardly through rotation thereof and this in turn will cause rearward movement of the rod member 20 and subsequent removal of the case from what may be referred to as a seized position within the barrel. After the case has been moved rearwardly to a sufficient extent, compression of spring 52 results in a "popping-out" action of the latter so that ejection of the ruptured cartridge case is practically automatic.

In operation, pressure is applied to the plunger element. This allows the parts 10, 20 and 40, which as explained, are what may be called flexibly associated with one another, to move further into the barrel B at the same time that the spring 52 is compressed against shoulder 60 which is provided within part 32, as shown.

As a consequence, member 10 will move forwardly a sufficient distance in order to snap over the forward edge of the ruptured cartridge. The member 10, being expandable, as stated, will remain in this cartridge-engaging position and at this time the spring 52 will allow the parts to return to their original positions, which is to mean that the head part 22 of spindle member 20 locks the shoulder of collet member 10 in position.

Then, while housing member 26 remains fixed against the bearing surface of the barrel B as above described, the sleeve member 32 is rotated to pull the case out of the barrel. During this easing-out step the spring is compressed by means of the plunger 50 and the extraction is complete. Of course, in order to remove the cartridge case from the device, the housing must be removed from association with member 32, merely by unthreading the same.

I claim:

1. As a new article of manufacture, a device for extracting a ruptured cartridge case from the barrel of a firearm comprising in combination, a cone headed collet member with a reduced body portion thereby providing an annular shoulder therebetween and having a bore therethrough terminating in a conical interior surface in said headed portion, said headed portion comprising resilient members provided to contract when inserted through the bore of the ruptured cartridge case, a cone headed spindle member disposed within said collet member adapted to expand said resilient members whereby the front rim of the ruptured cartridge is engaged by said shoulder, a housing member having a threaded bore therein, a sleeve member threadably engaged within said housing member and releasably engaged with said spindle member whereby rotating said sleeve

member causes said housing member to bear against the rear end face of the barrel and said spindle member to be drawn rearwardly extracting the cartridge case from the barrel.

2. As a new article of manufacture, a device for extracting a ruptured cartridge case from the barrel of a firearm comprising in combination, a cone headed collet member with a reduced body portion thereby providing an annular shoulder therebetween and having a bore therethrough terminating in a conical interior surface in said headed portion, said headed portion comprising resilient members provided to contract when inserted through the bore of the ruptured cartridge case, a cone headed spindle member disposed within said collet member adapted to expand said resilient members whereby the front rim of the ruptured cartridge is engaged by said shoulder, a housing member having a threaded bore therein, a sleeve member threadably engaged within said housing member and provided with a T-slot in its forward end portion, a connecting member having its forward end threadably engaged with said spindle member and its rear end portion seated in said T-slot of said sleeve member whereby rotating said sleeve member causes said housing member to bear against the rear end face of the barrel and said spindle member to be drawn rearwardly extracting the cartridge case from the barrel.

3. As a new article of manufacture, a device for extracting a ruptured cartridge case from the barrel of a firearm comprising in combination, a cone headed collet member with a reduced body portion thereby providing an annular shoulder therebetween and having a bore therethrough terminating in a conical interior surface in said headed portion, said headed portion comprising resilient members provided to contract when inserted through the bore of the ruptured cartridge case, a cone headed spindle member disposed within said collet member adapted to expand said resilient members whereby the front rim of the ruptured cartridge is engaged by said shoulder, a housing member having a threaded bore therein, a sleeve member threadably engaged within said housing member and provided with a T-slot in its forward end portion, said sleeve member having a bore in the rear end portion and a smaller hole connecting said bore and said T-slot, a spring pressed plunger slidably mounted in said bore of said sleeve, a connecting member having a threaded hole in the rear end portion to threadably secure said spring pressed plunger, said connecting member having its forward end threadably engaged with said spindle member and its rear end seated in said T-slot of said sleeve member whereby rotating said sleeve member causes said housing member to bear against the rear end face of the barrel and said spindle member to be drawn rearwardly extracting the cartridge case from the barrel.
